ATTORNEY.

UNITED STATES PATENT OFFICE.

SAMUEL S. GOLDMAN, OF ST. LOUIS, MISSOURI.

WASHING-MA HINE.

1,353,829.

Specification of Letters Patent. Patented Sept. 28, 1920.

Application filed April 29, 1919. Serial No. 293,393.

To all whom it may concern:

Be it known that I, SAMUEL S. GOLDMAN, a citizen of the United States, residing at the city of St. Louis, State of Missouri, have 5 invented a certain new and useful Improvement in Washing-Machines, of which the following is a specification, reference being had to the accompanying drawing, forming a part thereof.

10 This invention relates generally to washing machines and, more particularly, to a certain new and useful improvement in washing machines of the type wherein the washing is accomplished by movements of 15 the clothes container.

The principal objects of my present invention are to provide a washing machine of simple and inexpensive form and construction in which a suds-box is arranged for 20 movements to impart to its suds-content and the goods to be washed a defined course of undulated or rocking reciprocation, in the surges of which, that is at the terminals of the course, the goods are elevated in a loosened or relatively separated condition and brought with force to "break" with the wave of the suds-content at the ends of the suds-box; to provide a frame and operating mechanism for the suds-box of simple, rigid, 25 and economical construction; to provide the suds-box with "pounders" in the form of funnel-shaped devices over which the goods "break" in a manner to facilitate the forcing of the suds-content through the goods; 30 to provide means for heating the suds-content, if desired, during the operations of the machine; and to improve generally upon washing machines of the type stated.

With the above and other objects in view, 35 my invention resides in the novel features of form, construction, arrangement, and combination of parts hereinafter described and afterward pointed out in the claim.

In the accompanying drawing, 40 Figure 1 is a plan view of a washing machine constructed in accordance with and embodying my invention;

Fig. 2 is a side elevational view of the machine, parts of the supporting-frame being broken away and the suds-box being 45 partly shown in section;

Fig. 3 is an end elevational view of the machine, a wringer and a gear therefor being shown in connection with the machine;

Fig. 4 is a fragmental longitudinal sectional view of the suds-box and the clothes-pounders therein; and

Fig. 5 is a detail sectional view of one of the suds-box hanger-bearings.

Referring more in detail to the said drawing, in which like reference characters refer to like parts throughout the several views, 1 indicates the vertically disposed corners or legs of the frame-structure, which are preferably in the form of lengths of angle-iron 60 and which are rigidly connected by longitudinal rails 2 and transverse rails 3, and to which structure I preferably attach gussets, as at 4, to add rigidity thereto, the frame-structure taking the form, as shown, of a 65 rectangular oblong skeleton.

To the upper pair of longitudinal rails 2 and adjacent the opposite ends of the frame, are suitably fixed bearings 5 in which are 70 removably fitted bushings 6 provided with sockets 7 arranged for the suspension of bails 8, whose upper ends have balls 9 for bearing in the sockets 7, and by preference the bushings 6 are firmly held in position by drift-pins or the like 10.

The bails 8 are substantially U-shaped and engage and journal at their bights in bearings 11 fixed to a substantially rectangular skeleton frame or cradle 12, as I will term it, which, by reason of said bails and bearings, may be freely oscillated or swingingly 75 reciprocated.

Removably mounted upon or in the cradle 12, and firmly retained thereupon against accidental displacement in the oscillations of the cradle by the upright cradle angular corner-pieces seen particularly in Fig. 1, is a suds-box 13 also of substantially rectangular form and preferably provided with a hopper-shaped overhanging top or inwardly 90 and downwardly inclined flange 14, in which is fitted a removable cover or lid 15.

Secured within and to the sides of the suds-box 13 adjacent to and spaced from each end and disposed vertically thereof, is 100 a transverse diaphragm or partition 16 with its lower edge above the bottom of the suds-box and its upper edge spaced from and beneath the overhanging flange 14, each of said diaphragms or partitions having a plurality of relatively spaced perforations, and in each of which perforations a clothes-pounder, so called, in the form preferably 105

of a funnel 17, as best shown in Fig. 4, is fitted at its smaller end to project longitudinally of the suds-box.

For operating the machine by power, I preferably employ a suitable motor 18 mounted on sleepers 19 disposed on the lower longitudinal rails 2 and belted or otherwise drivingly connected with a pulley 20 fixed on a shaft 21 mounted for rotation in bearings 22 provided on the frame-structure. 23 indicates a second shaft also mounted for rotation in bearings 24 provided on the frame-structure somewhat above the bearings for the first shaft 21. 25 Connected at one end with one of the bails 8 for swingingly reciprocating or oscillating the cradle 12 and its carried suds-box 13, is a pitman 25, connected at its other end with a wrist-wheel 26 mounted on the shaft 23, 30 the rotary movement of first shaft 21 being reducingly imparted to shaft 23 and its carried wrist-wheel 26 by means of meshing-spur-gears or the like 27 and 28 fixed, respectively, on the shafts 21 and 23. 35 For heating the suds-content of the box 13, I preferably employ a gas-burner or the like 29 mounted upon a strap-bridge 30 supported on the lower frame-rails 2, as best seen in Fig. 2, and to which burner there is 30 suitably connected a supply-tube 31 leading from a suitable source of supply.

In the bottom of the suds-box 13 is preferably provided a drain-opening 32, in which is removably fitted a stopper 33, 35 whereby the emptying of the box of its suds-content may be facilitated.

In use or operation, the cradle 12 and its removably carried suds-box 13 are rocked or oscillated as described, thereby imparting to the contents of the suds-box a wave-like motion, which rises in surges at the ends of the suds-box and with crests which pass under the partitions 16 and rise up the ends of the box between the end walls and the partitions to be rolled or driven toward the center of the box by the overhanging flange or top 14. It is obvious that such water action will carry the goods being washed to the ends of the box and then, in the swell of the water, tend to relatively separate the goods, in which condition the goods will be "open" to receive the suds-content, then dashed against the pounders 17, where relatively broad areas of the goods are spread and held over the mouths of the funnels while the suds-content is being forced therethrough by the pressure of the water and also by the suction created by the passage of the water upwardly through the space 30 between the end of the box and the partition. From thence the wave continues on up the ends of the box in the space between the end wall and partition, where its crest is directed inwardly and downwardly by the 35 flange 14 over the areas of the goods held

over the funnels to, first, remove such foreign matter as may have been collected therein in the movement of water therethrough and, secondly, to quickly free the goods from the funnels, so that the goods 70 may travel with the water toward, and for similar treatment at, the other end of the box, such action of the water and of the goods being facilitated and increased by reason of the hopper-shaped overhanging 75 top 14 of the suds-box.

My new washing-machine is comparatively simple in form and construction, may be inexpensively and economically manufactured, and has been found exceedingly 80 efficient in operation.

It will be noted that the suds-box, being removable, may be conveniently taken from the supporting-cradle as may be required or desired, in washing operations or for repair 85 or substitution.

I am aware that minor changes in the form, construction, arrangement, and combination of the several parts of the machine may be made and substituted for those here 90 in shown and described without departing from the nature and principle of my invention. I may add that each of the bearings 5 is provided with an oil-duct 34 for convenient lubrication, the sockets 7 serving to 95 retain the lubricant so supplied and the sockets and their contained balls 9 providing a simple and efficient bearing for the oscillatory bails 8. It will be obvious that the bushings 6 may be conveniently renewed whenever required. 100

Having thus described my invention, what I claim and desire to secure by Letters Patent is:

A washing machine, comprising a frame, 105 a suds-box mounted to swing in said frame, inwardly projecting flanges at the top of said suds-box, vertically disposed partitions in said suds-box adjacent to and spaced from the ends thereof and having their 110 lower edges located above the bottom of the suds-box and their upper edges spaced from and beneath the inwardly projecting flanges at the top of the suds-box, a series of pounders fixed to said partitions and projecting 115 inwardly therefrom and communicating with the spaces between said partitions and the ends of the suds-box, and means for swinging said suds-box to surge the contents therein from end to end to cause the suds- 120 water to forcibly move the clothes into engagement with said partitions and the pounders thereon, a portion of the suds-water passing under the partition and up through the passage between the partition 125 and end of the suds-box to create a suction through said pounders.

In testimony whereof, I have signed my name to this specification.

SAMUEL S. GOLDMAN.
